UNITED STATES PATENT OFFICE.

HARRY B. HOPPIN, OF WORCESTER, MASSACHUSETTS, ASSIGNOR TO WARREN LEATHER
GOODS CO., OF WORCESTER, MASSACHUSETTS, A CORPORATION OF MASSACHUSETTS.

HAND BAGGAGE.

Application filed May 31, 1924. Serial No. 716,871.

To all whom it may concern:

Be it known that I, HARRY B. HOPPIN, a citizen of the United States, residing at Worcester, in the county of Worcester and State of Massachusetts, have invented a new and useful Hand Baggage, of which the following is a specification.

This invention relates to hand baggage such as suit cases, travelling bags, hat boxes and other similar articles. It is the general object of my invention to provide certain improvements in articles of this general type by which both the appearance and the utility of the articles will be substantially increased. With this general object in view, different features of my invention are shown in the drawings and described in the specification and will be more particularly set forth in the appended claims.

Referring to the drawings:

Fig. 1 is a partial top view of a suit case embodying the novel features of my invention;

Fig. 2 is a partial side elevation thereof; Figs. 3, 4 and 5 are detail sectional views, taken along the lines 3—3, 4—4 and 5—5 in Fig. 1;

Fig. 6 is a partial side elevation of a hat box embodying my improvements;

Fig. 7 is a partial plan view thereof; and

Fig. 8 is a partial side elevation of a travelling bag also embodying certain of my improvements.

Referring particularly to Figs. 1 to 5, I have shown a suit case comprising side members 10, end members 11, and top members 12. The side members 10 meet the end members 11 and top members 12 in corners which are covered and protected with reinforcing strips 13. These strips 13 are firmly secured to the body members by rows of stitching 14 as indicated in Fig. 5.

Along one edge of each re-inforcing strip 13 I insert a filler piece 15, which is preferably doubled to form a fold adjacent one outer edge of the strip 13. The filler piece 15 is secured in position by one of the rows of stitches 14 by which the strip 13 is attached.

The piece 15 forms a tight joint between the strip 13 and the body, and the fold of the filler material protects and partially conceals the edge of the strip 13.

When the filler piece 15 is made of a material which contrasts sharply in appear-

ance with the re-inforcing strip 13 and also with the body portion 12, the strip 13 adds materially to the pleasing appearance of the article.

A handle 20 is secured to the suit case 60 by links 21 and attaching devices 22, said devices being commonly formed of leather secured by stitching 23. The handle is provided with depressions 24 (Fig. 4) along the edges thereof and is also preferably 65 molded in convex form, as shown at 25, between the depressions 24. A layer of covering material 26 is placed over the convex portion 25 and the edges thereof are secured within the depressions 24 and are partially 70 concealed in said depressions.

The covering material 26 protects the body of the handle from injury and when of a color or material contrasting with the body portion of the handle, a pleasing and 75 ornamental effect is also attained.

I also find it desirable to insert a layer of material 27 under each attaching device 22, the edge of the layer 27 projecting beyond the edge of the device 22 and forming a border which may also be of a contrasting color or appearance.

In Figs. 6 and 7, I have shown the improvements above described as applied to a 80 hat box having the filler pieces 30, handle covering 31, and the interposed layers 32 under the handle attaching devices 33. In Fig. 8 I have shown the use of filler pieces 35 and 36 at different portions of the body of a hand bag.

Having thus described the details of construction of my improvements, it will be seen that I have added materially to both the appearance and utility of the articles of hand baggage herein described, protecting portions of the article from wear, and also concealing the edges of the reinforcing strips and preventing the entrance of moisture into the seams thereof.

Having thus described my invention and the advantages thereof, I do not wish to be limited to the details herein disclosed otherwise than as set forth in the claims, but what I claim is:

1. In hand baggage, body portions meeting to form a corner, a reinforcing strip covering said corner, means to secure said strip to said body portions along the edges thereof, and a filler piece interposed between said body and said reinforcing strip along 105

110

one edge of said strip and firmly secured in such position, said filler piece being folded, the fold projecting slightly beyond the edge of said reinforcing strip to form a bead adjacent the edge of said reinforcing strip.

2. In hand baggage, body portions meeting to form a corner, a reinforcing strip covering said corner, means to secure said strip to said body portions along the edges thereof, and a filler piece formed of material of different visual characteristics interposed between said body and said reinforcing strip along one edge of said strip and firmly secured in such position, said filler piece being folded, the fold projecting slightly beyond the edge of said reinforcing strip to form a bead adjacent the edge of said reinforcing strip, and contrasting in

appearance with said reinforcing strip and also with said body portions.

3. In hand baggage, a handle comprising a body portion of solid leather having a laterally extended cross section outwardly curved above and below at the middle portion of said section to form longitudinally extended enlarged portions, and having depressions along its upper edges at each side of said longitudinally extended upwardly curved portion, and a piece of covering material of contrasting appearance overlying the upwardly curved central upper portion of said handle, and having its edges secured in said depressions.

In testimony whereof I have hereunto affixed my signature.

HARRY B. HOPPIN.
